UNITED STATES PATENT OFFICE.

JOHN W. FOX, OF EAST HUNTINGDON TOWNSHIP, WESTMORELAND COUNTY, PENNSYLVANIA.

STONE-CUTTER'S CHISEL.

No. 822,205.

Specification of Letters Patent

Patented May 29, 1906.

Application filed March 1, 1906. Serial No. 303,699.

To all whom it may concern.

Be it known that I, JOHN W. FOX, a citizen of the United States, residing in East Huntingdon township, in the county of Westmoreland and State of Pennsylvania, have invented new and useful Improvements in Stone-Cutters' Chisels, of which the following is a specification.

This invention relates to improvements in stone-cutters' chisels.

The object of the invention is to provide a detachable bit or blade with peculiar and specific means for holding it in its handle.

In the drawings, Figure 1 is a vertical section of my improved chisel on the line 1 1, Fig. 2. Fig. 2 is a transverse section on the line 2 2, Fig. 1. Fig. 3 is a horizontal section on the line 3 3, Fig. 2. Fig. 4 is a side elevation of a slight modification. Fig. 5 is a cross-section of the same on the line 4 4, Fig. 4.

1 indicates a handle, chuck, or the like which is slightly flattened and beveled at its lower end 2 from the edge 3 to a point 4. Said beveled end is split, as shown at 5, to receive the bit 6 and forming two legs 2^a 2^a. A transverse slot 7 is formed in the beveled end 2 to receive the squared portion 8 of a clamp 9.

Clamp 9 is of peculiar formation and forms a most essential part of my invention. The head 10 of the clamp is disposed at an angle to the center of the square portion 8 to fit squarely the beveled face of one of the legs 2^a. This peculiar relationship between the body 35 of the clamp and the head positions the threaded end 11 at right angle to the beveled face of the opposite leg 2^a, as clearly shown in Fig. 1.

The bit 6 is oblong in outline and is adapted to be fitted in the split end of the handle and is provided with a square opening 13, through which the squared portion of the clamp passes. However, this exact shape of the opening is not necessary; but one wall 45 thereof must be straight to prevent the clamp turning.

To assemble the parts of the chisel, the bit 6 is placed in the split end 2 of the handle, its edge 12^a projecting beyond said handle sufficiently to form a cutting edge. Then the body 50 of the clamp is passed through the slot 7 and the square opening 13, head 9 fitting squarely against the beveled surface of leg 2^a and the free threaded end 11 inclining downwardly

at right angle to the opposite beveled surface 55 of leg 2^a, where a binding-nut 13 is applied to clamp the two legs tight against the bit. It will be noted that when the parts are assembled the head of the clamp and the nut form a beveled way corresponding to the 60 beveled end of handle 2. The object of this relationship of parts is essential to the practical operation of my invention, in that as a blow is imparted to the chisel the tendency is to drive the bit and the handle toward each other, resulting in forming a more substantial binding action of the clamp on the beveled surfaces of the handle, consequently insuring of the holding of the bit in place. 70

The opening in the bit and the slot 5 corresponding to the shape of the body of the clamp, the bit cannot turn, which is necessary in a tool of this character.

Obviously the bit may be made thin 75 enough that it may sharpen itself while being operated—that is to say, as one side wears down the opposite edge is sharpened, and by turning over the tool the other side may be simultaneously treated. 80

In Figs. 4 and 5 I have shown my improvement used in connection with an etching-tool 20. These tools are usually very thin and cannot withstand an unusual blow without being deflected laterally. To meet this 85 requirement, the inner edges of the legs 21 are formed with flanges 22, which embrace the edges of the tool and hold it against lateral movement. The upper end of the tool is made wider than the lower end to 90 strengthen it and is secured to the handle in exactly the same manner as heretofore described.

What I claim is—

1. A chisel, comprising a handle which is 95 beveled and split at its end and formed with a slot, a bit fitted in the split end, said bit having an opening a threaded clamp having a stem which passes through the slot in the handle and the opening in the bit and having 100 a head at an angle, the angle of the head corresponding to the adjacent beveled side of the handle, and a nut engaging the threaded end of the clamp and bearing on the opposite beveled side of the handle, to clamp the bit 105 in the split end of said handle, whereby when a blow is imparted to the chisel the bit will be more rigidly held to the handle.

2. A chisel, comprising a handle which is beveled and split at its end and formed with a slot, a bit fitted in the split end, said bit having an opening, clamping means passing through the slot in the handle and the opening in the bit and including means fitting the beveled sides of the handle, whereby when a blow is imparted to the chisel the bit will be more rigidly held to the handle.
- 10 3. A chisel, comprising a beveled handle which is split at its end and formed with a slot, a bit fitting in the split end and formed with a square opening, a clamp having a square portion and a head at an angle to said square portion, said head impinging one beveled side of the handle and the square portion passing through the slot and the square opening in the bit, and a nut screwed on the clamp and impinging the opposite beveled surface 15 of the handle, a blow on the chisel causing the bolt to clamp the bit and handle together.
- 20 4. A chisel, comprising a beveled handle split at one end and formed with a slot, a bit having an opening with one wall straight, a 25 clamp having a flat surface extending

through the slot in the handle and the opening in the bit on a line at a right angle to one of the beveled surfaces of the handle and including a head to engage one beveled surface, and adjusting means which fits against the 30 opposite beveled surface of the handle to bind the bit in the split end, the flat surface of the clamp coöperating with the straight wall of the opening in the bit to prevent said clamp turning.

35 5. A chisel comprising a handle which is beveled and split at its end and formed with a slot, flanges formed at the edges of the split to embrace a bit, a bit fitted in the split end of the handle and formed with a clamp-receiving opening, a clamp passing through the slot in the handle and the opening in the bit and engaging the opposite sides of the beveled handle.

40 In testimony whereof I affix my signature 45 in presence of two subscribing witnesses.

JOHN W. FOX.
